UNITED STATES PATENT OFFICE.

SYLVESTER S. MARVIN, OF BRYN MAWR, AND WILLIAM MUNZ, OF PHILADELPHIA, PENNSYLVANIA, ASSIGNORS TO PENNSYLVANIA CHOCOLATE COMPANY, OF PITTSBURGH, PENNSYLVANIA, A CORPORATION OF PENNSYLVANIA.

CHOCOLATE AND CANDY MACHINE.

1,349,844.

Specification of Letters Patent. Patented Aug. 17, 1920.

Application filed October 8, 1919. Serial No. 329,400.

To all whom it may concern:

Be it known that we, SYLVESTER S. MARVIN and WILLIAM MUNZ, citizens of the United States, residing, respectively, at Bryn Mawr, 5 in the county of Montgomery and State of Pennsylvania, and at Philadelphia, in the county of Philadelphia and State of Pennsylvania, have jointly invented certain Improvements in Chocolate and Candy Machines, of which the following is a specification.

This invention relates to improved means for delivering carriers, in the form of trays or pans, for deposits of the materials used 15 in making chocolate and candy, such as nut bars or other forms.

The improvements comprise an inclined way down which the carriers are moved in succession to a revolute feeding device 20 operating with reciprocatory devices for receiving and delivering them to carrying mechanism which translates them over a table to receive the deposits of materials.

In the preferred construction, the invention 25 comprises a vertically reciprocating table, an intermittently moving conveyer adapted for carrying trays over the table in synchronized relation to the latter's movements, oscillatory means for receiving trays 30 and delivering them upon the table in correct position with relation to the conveyer, means operated by the rise of the table to open the supports with the release of the trays so as to permit them to drop upon the 35 table and by the descent of the table to close the supports so as to hold the succeeding trays until delivered by the sequential rise of the table; a roller provided with a pliable periphery revolved intermittently in sequential 40 relation to the coating mechanism for the purpose of delivering the trays to the supports, a reciprocating device operated by the table to compel the correct delivery of trays from the roller to the supports, and mechanism for effecting the cooperation 45 of the several parts so that they will perform their functions in the desired synchronous relation.

The characteristic features of the invention 50 are embodied in the mechanism set out in the following description and the accompanying drawings in illustration thereof.

In the drawings, Figure 1 is a broken top

plan view of mechanism comprised in the invention; Fig. 2 is a broken part sectional 55 side elevation of the same showing additional details of the construction; Fig. 3 is a broken vertical sectional view taken on the line 3^x—3^x of Figs. 1 and 2; Fig. 4 is a broken side elevation of mechanism for effecting the coördinate operations of the table, conveyer and tray delivery mechanism; Fig. 5 is a sectional view on the lines 5^x—5^x of Figs. 1 and 2, and Fig. 6 is a sectional view on the lines 6^x—6^x of Figs. 65 2 and 3.

The mechanism illustrated comprises the frame 1 of a depositing machine having a vertically movable table 2. The table is provided with and elevated by the struts 3 70 having the bifurcated guides 4, yoked on the shafts 5 journaled in the frame, and rollers 6 bearing on cams 7 fixed on the shafts.

Link belts 8, provided with the fingers 8', 75 are carried over sprocket wheels 9 fixed on shafts 10 which are journaled in the ends of the table, the belts moving in the parallel ways 2' extending longitudinally of the table. 80

Struts 11 support the tray feeding mechanism, comprising the inclined ways 12 in the form of angle bars disposed above the table 2. The struts 11 are provided with the bearings 11' containing the slots 11" 85 through which they are adjustably engaged to the frame 1 by the bolts 13 and by which the open way comprising the angles 12 can be varied in width.

Brackets 14 are clamped in adjustable relation to the struts 11, through the slots 11''' thereof, by the bolts 15, the brackets being provided with the bearings 14' in which is journaled the shaft 16 extending therethrough and through the struts. 95

The shaft 16 is revolved by a sprocket wheel 17 and revolves a spur gear 18, both fixed thereon.

The brackets 14 are provided with the further bearings 14'' in which is journaled 100 the shaft 19, the shaft having fixed thereon a spur gear 20 engaged by the spur wheel 18 and a roller 21 provided with a pliable periphery 21' which may be felt.

It will be noticed that the roller 21 can be 105 set relatively to the ways 12 down which,

under the guides 22 thereon, the trays 23 slide to the roller which controls their movement and feeds them forward one by one.

An angle bar 24 extends across the machine, in front of the roller 21, and is provided with the end blocks 25 adapted to bear upon the sides of the frame 1. Guide pins 26, extending through the horizontal leg or flange of the bar 24 and through the blocks 25 engaged therewith, are set in the frame flanges 1' on which the blocks rest, and bolts 27, extending through such blocks and flanges, support the coiled springs 28 between their lower ends and the flanges 1', whereby the bar and its connections are permitted a restrained vertical movement, in case of jamming in feeding the trays.

Angles 29 are fixed vertically, in laterally adjustable relation to the vertical leg or flange of the bar 24, by the bolts 30 passing through the slots 24' thereof, the legs of the angles extending transversely to the bar having reversely disposed angles 31 fixed thereto through the intermediate vertical legs of the angles 32 which are fixed by the splice plates 33 to the angles 12.

Split journal bearings 34 are fixed on the laterally extending top legs or flanges of the angles 32 and are adjusted by set screws 35. Yokes 36 are rocked on the bearings 34 by means of the pintles 37 journaled therein. The yokes 36 carry the angles 38 with ends 38' which provide hinged tray supports adapted to be held in line with the angles 12 and to be swung backward for the purpose of dropping trays (delivered thereto by the roller 21) upon the table 2, the movements of the supports being regulated by adjusting the screws 35 to regulate the movements of the pintles 37 to which the yokes are fixed.

Each yoke 36 is provided with an arm 36' which is journaled on a stud 37^a of a collar 37^b. Bolts 38^a extend through the collars 37^b and have adjustable nuts 39 and 40 thereon, on opposite sides of the collars. The bolts 38^a are provided with the bearings 41 adjustably fixed to the table by the slots 41' therein, through which pass the bolts 42, the bearings having thereon the guides 43 for the trays dropped upon the table 2.

An arm 44, provided with a resilient finger 44', is connected with one of the yokes 36 and is oscillated thereby in front of the roller 21 so as to impinge upon trays passing thereunder.

As the table 2 rises, the nuts 40 on the bolts 38^a elevate the collars 37^b, which act 60 through their pintles 37^a and the arms 36' to swing the yokes 36 rearwardly, thus separating the supports 38, depressing the arm 44 and thereby depositing the tray delivered by the roller 21 upon the table 2, there to

be engaged by the fingers 8' of the chains 8 65 and advanced over the table.

The operations are effected so that the functions are performed in synchronous relation by the following coördinated driving mechanism. A power shaft 45, journaled 70 in the frame 1, has fixed thereon a pinion 45 which engages and drives a spur wheel 46 containing a concentric slot 46'; the spur wheel being fixed on a shaft 47 which is journaled in the frame. A pinion 48, fixed 75 on the shaft 47 drives the spur wheel 49 fixed on the shaft 5, by which the table 2 is reciprocated through the cam 7. A pitman rod 50 is connected at one end by a bolt 51 with the slot 46' and at the other end by a 80 bolt 52 with a lever 53 which rocks on a shaft 54 journaled in the frame, the lever carrying a pawl 55 which engages a ratchet wheel 56 fixed on the shaft. A sprocket wheel 57, fixed on the shaft 54, acts through 85 a sprocket chain 58 on a sprocket wheel 59 fixed on a shaft 60 which is journaled in the frame. The shaft 60 has a sprocket wheel 61 thereon which acts through a sprocket chain 62 on a sprocket wheel 63 fixed on the shaft 10, which revolves the sprocket wheels 9 and operates the carrying belts 8 intermittently. A further sprocket wheel 64 on the shaft 60 is connected by the chain 65 with the sprocket wheel 17 on the shaft 16, 95 from which the roller 21 is operated intermittently through the gears 18 and 20.

Having described our invention, we claim:

1. In a machine of the character described, the combination with a vertically reciprocating table and conveying mechanism movable over said table, of an inclined way, a device for controlling the movement of articles along said way to said table, reciprocating means to which said device delivers 105 said articles, and mechanism whereby the movements of said table operate said means and articles held thereby are delivered to said conveyer.

2. In a machine of the character described, 110 the combination with a vertically reciprocating table and conveyer mechanism movable over said table, of means operated by the reciprocations of said table for delivering articles to said conveyer.

3. In a machine of the character described, the combination with a vertically reciprocating table and conveyer mechanism movable over said table, of mechanism comprising oscillatory means for delivering articles to said conveyer, and mechanism whereby the reciprocations of said table effect the oscillations of said means.

4. In a machine of the character described, the combination with a vertically reciprocating table and conveyer mechanism for carrying articles over said table, of mechanism comprising reciprocating means for

delivering articles to said conveyer, mechanism operated by the rise of said table for operating said reciprocatory means to effect the release of an article held thereby, and means whereby said table and said conveyer mechanism are operated intermittently in synchronous relation.

5. In a machine of the character described, the combination with a table and conveyer mechanism for carrying articles over said table, of feeding mechanism for delivering articles to said conveyer mechanism, said feeding mechanism comprising an inclined way, a roller for controlling the movement 10 of articles over said way, and reciprocatory means to which said roller delivers said articles and by which said articles are delivered to said table and conveyer mechanism.

6. In a machine of the character described, the combination with a table and conveyer mechanism for carrying articles over said table, of feeding mechanism for delivering articles to said conveyer mechanism, said feeding mechanism comprising a feed roller, 20 and reciprocatory means to which said roller delivers said articles and by which said articles are delivered to said conveyer and table.

7. In a machine of the character described, the combination with a vertically reciprocating table, conveyer mechanism for carrying articles over said table, reciprocatory delivery mechanism for delivering articles to said table and conveyer mechanism, and means whereby said table, conveyer mechanism and delivery mechanism are operated synchronously so that said table shall be elevated, 30 said conveyer mechanism shall be stationary and said delivery mechanism shall be open simultaneously.

8. In a machine of the character described, the combination with a vertically reciprocating table, conveyer mechanism movable over said table and means for moving said table and mechanism intermittently in synchronous relation, of feeding mechanism comprising oscillatory means for delivering articles to said table, and means carried by 40 said table for operating said oscillatory means.

9. In a machine of the character described, the combination with a vertically reciprocating table, conveyer mechanism movable over said table, and means for moving said table and mechanism in synchronous relation, of feeding mechanism comprising a 50 roller, means whereby said roller is operated in synchronous relation to the movement of said table and conveyer, oscillatory devices to which articles are delivered by said roller, and means carried by said table whereby its rise rocks said devices to deliver an article held thereby and its fall rocks said devices oppositely to position for holding an article delivered thereto by said roller.

10. In a machine of the character de-

scribed, the combination with a table and a conveyer for carrying articles over said table, of means supported above said table for feeding articles thereto, and resilient mechanism for holding said means in movable relation to said table.

11. In a machine of the character described, the combination with a frame, of inclined ways having means for fixing them in relatively adjustable relation to said 70 frame, bearings carried by said ways and a feed roller journaled in said bearings.

12. In a machine of the character described, the combination with a frame, of means comprising an inclined way supported 75 by said frame, a roller having a pliable periphery for feeding articles moving down said way, hinged supporting devices for holding articles fed thereto by said roller, and mechanism for rocking said devices to 80 deliver articles held thereby.

13. In a machine of the character described, the combination with a frame, of means comprising a way supported by said 85 frame, a roller for feeding articles delivered thereto by said way, supporting devices for holding articles delivered thereto by said roller, means for operating said supporting devices to release said articles held thereby, and means adapted to impinge upon said articles to compel their delivery from said supporting devices.

14. In a machine of the character described, the combination with a way, of a roller for feeding articles delivered thereto 100 by said way, supporting means for holding articles delivered thereto by said roller, mechanism for rocking said supporting means, and an arm carried by said supporting means for impinging upon articles 105 held by said supporting means and compelling their delivery therefrom.

15. In a machine of the character described, the combination with a vertically reciprocating table and a conveyer for carrying articles over said table, of mechanism 110 for feeding said articles and positioning them relatively to said table and conveyer, said mechanism comprising hinged supports for said articles, mechanism whereby the reciprocations of said table rock said supports and guards carried by said table beneath said supports.

16. In a machine of the character described, the combination with a vertically 115 reciprocating table and a conveyer for carrying articles over said table, of mechanism for delivering said articles and positioning them relatively to said table and conveyer, said mechanism comprising oscillatory devices with arms thereon for holding and delivering said articles, collars provided with pintles engaging said arms, and means comprising bolts fixed to said table and extending through said collars whereby said table 125

opens said devices as it approaches the limit of its upward movement and closes said devices as it approaches the limit of its downward movement.

5. 17. In a machine of the character described, the combination with a vertically reciprocating table and a conveyer movable over said table, of mechanism for feeding and delivering trays to said table and conveyer, said mechanism comprising an inclined way, a roller for controlling the movement of trays along said way, oscil-

latory means comprising journals for receiving said trays from said roller and delivering them to said table and conveyer, 15 bearings having means for frictionally restraining the oscillatory movements of said pintles therein, and means whereby said table rocks said oscillatory means.

Signed at Philadelphia, in the county of 20 Philadelphia and State of Pennsylvania this 6th day of October, 1919.

SYLVESTER S. MARVIN.
WILLIAM MUNZ.
